N-(CYANOALKYL)-ENDO-PERHYDRO-4,7-
METHANOISOINDOLES

James W. Bolger, Canoga Park, Calif., assignor to Riker Laboratories, Inc., Northridge, Calif., a corporation of Delaware
No Drawing. Filed July 27, 1962, Ser. No. 213,004
5 Claims. (Cl. 260—319)

This invention relates to compositions of matter classified in the art of chemistry as substituted isoindoles.

The invention sought to be patented resides in the concept of a chemical compound in which there is attached to the nitrogen atom of an endo-perhydro-4,7-methanoisoindole nucleus or its hereinafter disclosed equivalents a cyano-lower alkyl group.

As used throughout the specification and in the claims the terms "lower alkyl" and "lower alkylene" embrace straight and branched chain alkyl and alkylene radicals, respectively, containing 1 to 6 carbon atoms and the term "cyano" denotes the monovalent $-\text{CN}$ radical.

The tangible embodiments of this invention, possess the inherent general physical characteristics of being, in the form of their acid addition salts, white crystalline solids. Spectral data reveal no unsaturation except as present in the nitrile group. The aforementioned physical characteristics, taken together with the nature of the starting materials and the mode of synthesis, positively confirm the structure of the compounds sought to be patented.

The tangible embodiments of this invention possess the inherent applied use characteristics of having significant pharmacological activity as anti-Parkinson and anti-hypertensive agents as determined by recognized and accepted pharmacological test procedures, and, in addition are valuable chemical intermediates in the preparation of other substituted isoindoles having significant pharmacological activity. For example treatment of these compounds with hydroxylamine yields the pharmacologically active N-amidoximo-lower alkyl-endo-perhydro-4,7-methanoisoindoles which are described and claimed in my application entitled "N-Amidoximo-Alkyl-Endo-Perhydro-4,7-Methanoisoindoles," Serial No. 213,047, filed July 27, 1962.

The manner and process of making and using the invention will now be generally described so as to enable a person skilled in the art of chemistry to make and use the same as follows:

The starting materials for the compounds of this invention, N-(halo-lower-alkyl)-endo-perhydro-4,7-methanoisoindoles and their 7a-substituted equivalents are prepared according to the method described in my application entitled "N-(Haloalkyl)-Endo-Perhydro-4,7-Methanoisoindoles," Serial No. 213,050, filed July 27, 1962. The starting materials are prepared as described in my aforementioned application by treatment of N-(hydroxy-lower alkyl)-endo-perhydro-4,7-methanoisoindoles with a thionyl halide or with a hot hydrohalic acid in the presence of an inert solvent.

2

The preparation of the tangible embodiments of this invention is illustrated as follows:

25 where A is lower alkylene, R is hydrogen or its herein-after disclosed equivalent and X is halogen.

Starting materials bearing at the 7a-position a lower alkyl or phenyl group, or such group bearing one or more substituents such as lower alkoxy, halogen, trifluoromethyl, or lower alkyl in the case of phenyl, are the full equivalent of the N-halo-lower alkyl-endo-perhydro-4,7-methano starting materials in the foregoing reaction sequence, thereby to produce 7a-substituted N-cyano-lower-alkyl finished products which have the same utility as N-cyano-lower-alkyl-endo-perhydro-4,7-methanoisoindoles.

30 The reaction depicted hereinabove is carried out by treating the starting material with an alkali metal cyanide such as, for example, sodium cyanide, according to the method described by Friedman and Schlechter (J. Org. Chem. 25:877 (1960)).

35 Alternately, such N-(cyano alkyl) substituted isoindoles can be prepared by the treatment of the 7a-substituted or unsubstituted isoindole having a hydrogen substituent on the ring nitrogen atom with an unsaturated nitrile having a terminal double bond, such as acrylonitrile.

40 The tangible embodiments of this invention can, if desired, be converted into their non-toxic pharmaceutically acceptable acid addition and quaternary ammonium salts by conventional procedures. Typical acid addition salts include the hydrochloride, hydrobromide, citrate, maleate, sulfate, nitrate and the like. Typical quaternary ammonium salts are those formed with such alkyl halides as methyl iodide, ethyl bromide, n-hexyl bromide and the like. Such salts are the full equivalents of the free bases and are included within the scope of this invention.

45 The tangible embodiments of this invention, either as the free base or in the form of a non-toxic pharmaceutically acceptable acid addition or quaternary ammonium salt, may be combined with conventional diluents and carriers, to form such dosage forms as tablets, capsules, solutions, suspensions, suppositories and the like.

The best mode contemplated by the inventor of carrying out this invention will now be set forth as follows:

EXAMPLE 1

(a) *N*-(2'-*Cyanoethyl*)-*Endo*-*Perhydro-4,7-Methanoisoindole Hydrochloride*

Endo-perhydro - 4,7-methanoisoindole hydrochloride (49.4 g., 0.288 mole) is converted to the free base by dissolving it in a strongly alkaline solution and extracting with ether. The ether extract is dried with anhydrous magnesium sulfate and then concentrated in vacuo. Water (4 ml.) is added to the ethereal residue and sufficient dimethylformamide is added to solubilize the mixture. The mixture is stirred and heated at 80° C. while acrylonitrile (15.3 g., 0.288 mole) is added dropwise. The reaction mixture is kept at 80° C. for one hour, cooled and then fractionally distilled in vacuo. Yield: 47 g. (86%), B.P. 115-117° C./1 mm. Hg. The free base dissolved in ether is converted to the hydrochloride salt with gaseous hydrogen chloride, M.P. 237-238° C.

Analysis.—Calculated for $C_{12}H_{21}N_2Cl$ (M.W. 226.75): C, 63.56%; H, 8.45%; Cl, 15.64%. Found: C, 63.76%; H, 8.47%; Cl, 15.39%.

(b) *N*-(2'-*Cyanoethyl*)-*N*-*Methyl-Endo-Perhydro-4,7-Methanoisoindole Iodide*

N-(2'-cyanoethyl)-endo-perhydro-4,7-methanoisoindole hydrochloride (15 g., 0.0662 mole), prepared as described in step "a," is dissolved in 50 ml. of water and made basic with concentrated sodium hydroxide. The resulting basic solution is extracted with ether. The ether extract is dried over anhydrous magnesium sulfate and the ether is removed by evaporation. The residue is mixed with 75 ml. of acetone and 15 ml. of methyl iodide, then allowed to stand at room temperature for 5 hours. A white crystalline solid appears which is recrystallized from methanol/ether (anhydrous). Yield: 18.5 g. (84%), M.P. 201° C. (d).

Analysis.—Calculated for $C_{13}H_{21}N_2I$ (M.W. 332.24): C, 47.00%; H, 6.37%; I, 38.20%. Found: C, 47.16%; H, 6.31%; I, 38.02%.

EXAMPLE 2

N-(3'-*Cyanopropyl*)-*Endo*-*Perhydro-4,7-Methanoisoindole Hydrochloride*

N-(3'-chloropropyl)-endo-perhydro-4,7-methanoisoindole hydrochloride (25 g., 0.1 mole) is converted to the free base and added slowly to a rapidly stirred, hot (100° C.) solution of dimethylsulfoxide (80 ml.) containing sodium cyanide (5.4 g., 0.11 mole). The temperature is kept constant for 2 hours, then the reaction mixture is cooled and 100 ml. of water is added. The product

is extracted with ether and the ether is then removed by evaporation leaving an oil which is distilled in vacuo. The product distilled at 120-125° C./1 mm. Hg. The hydrochloride salt is made in ether with gaseous hydrogen chloride and the resulting white powder is recrystallized from ethanol/ether (anhydrous). Yield: 16.5 g. (67%), M.P. 205-206° C.

Analysis.—Calculated for $C_{13}H_{21}N_2Cl$ (M.W. 240.78): C, 64.83%; H, 8.79%; Cl, 14.72%. Found: C, 64.75%; H, 8.79%; Cl, 14.76%.

The following example illustrates the preparation of other tangible embodiments of this invention.

EXAMPLE 3

N-(2'-*Cyanoethyl*)-7a-*Methyl-Endo-Perhydro-4,7-Methanoisoindole Hydrochloride*

N-(2'-chloroethyl)-7a-methyl-endo-perhydro-4,7-methanoisoindole hydrochloride (10 g., 0.040 mole) is converted to the free base and added slowly to a rapidly stirred, hot (100° C.) solution of dimethylsulfoxide (40 ml.) containing sodium cyanide (2.13 g., 0.0435 mole). The temperature is kept constant for 2 hours, then the reaction mixture is cooled and 100 ml. of water is added. The product is extracted with ether and the ether removed by evaporation. The hydrochloride salt is made in ether with gaseous hydrogen chloride and the resulting product is recrystallized from ethanol. Yield: 5.7 g. (59%), M.P. 225° C. (d).

Analysis.—Calculated for $C_{13}H_{21}N_2Cl$ (M.W. 240.78): C, 64.84%; H, 8.79%; Cl, 14.73%. Found: C, 64.59%; H, 8.81%; Cl, 14.80%.

The subject matter which the applicant regards as his invention is particularly pointed out and distinctly claimed as follows:

35 1. A compound of the formula

wherein R is a member selected from the group consisting of hydrogen and lower alkyl and A is lower alkylene.

45 2. *N*-(2'-cyanoethyl)-endo-perhydro-4,7-methanoisoindole.

3. *N*-(2'-cyanoethyl)-*N*-methyl-endo-perhydro-4,7-methanoisoindole iodide.

4. *N*-(3'-cyanopropyl)-endo-perhydro-4,7-methanoisoindole.

5. *N*-(2'-cyanoethyl)-7a-methyl-endo-perhydro-4,7-methanoisoindole.
